UNITED STATES PATENT OFFICE.

EUGÈNE SCHNEIDER, OF PARIS, FRANCE, ASSIGNOR TO SCHNEIDER & CIE., OF PARIS,
FRANCE, A LIMITED JOINT-STOCK COMPANY OF FRANCE.

APPARATUS FOR SELF-HOOPING TUBES.

Specification of Letters Patent.

Patented May 4, 1920.

1,338,872.

Application filed March 31, 1919. Serial No. 286,502.

To all whom it may concern:

Be it known that I, EUGÈNE SCHNEIDER, citizen of the French Republic, and residing at 42 Rue d'Anjou, Paris, France, have 5 invented new and useful Improvements in Apparatus for Self-Hooping Tubes, which invention is fully set forth in the following specification.

In the manufacture by the "self-hooping" 10 process of metal tubes of great strength having, like gun barrel tubes, an external longitudinal profile tapering relatively to the axis of the tube, from one end to the other thereof, either continuously or in consecutive steps, it is very important that the deforming pressures applied to the various zones of the tube should vary according to the said profile, or more exactly, according to the varying strains to which the said 15 various zones are respectively subjected in the firing of the gun.

This result has been obtained only to a partial extent by the usual processes for "self-hooping" by consecutive zones. In 20 fact it is obvious, if a portion of a tube having externally a continuous taper be divided into consecutive zones, that a tube having externally the inclined profile indicated by the line A—A in the diagrammatic Figure 1, will give a deformation curve 25 composed of stepped sections such as $a^1—a^1$, $a^2—a^2$, $a^3—a^3$ . . .

If the pressure that will have been applied to the zone Z^1 of the tube is suitable 30 for the mean thickness of the said zone, then the said pressure will be insufficient in the first portion of the said zone, and excessive in the second portion. The same applies to the following zones Z^2 , Z^3 , &c. This 35 drawback may be remedied to some extent by dividing the tube into a large number of zones which will render the operation long and costly.

The improved apparatus of the present 40 invention allows of effecting systematically the "self-hooping" of a tube of any external longitudinal profile. In other words the improved apparatus allows of varying in a continuous manner according to a given 45 law the internal pressure which is applied in a known way between the internal wall of the tube and the external wall of a mandrel; the said given law of variation coinciding very closely with the law of varia-

tion of the strains to which the tube is subjected at different points of its length. 55

For this purpose, the liquid under pressure, which is confined around the mandrel, between a joint at the head and a joint at the end, is compressed by means of a rearward movement imparted to the mandrel, and the liquid, thus compressed, in passing through an axial passage in the mandrel, acts upon a loaded valve mounted in a discharge passage arranged in an outer ex- 65 tension of the said mandrel.

In this manner by an automatic mechanism controlled by the movement of the mandrel, the load on the valve can be varied according to a given law, so that the said 70 valve shall be kept on its seat or shall be lifted by determined strains at determined points of the course of the mandrel.

Since the liquid is confined under pressure in the annular space comprised between 75 the mandrel and the internal wall of the tube, the movement of the said mandrel may be produced by various means, for instance by the action of a liquid under pressure that exerts a pull or a thrust upon the man- 80 drel. The mechanism for automatically regulating the load on the valve by the displacement of the mandrel may likewise be constructed in various ways.

Some constructional forms of the im- 85 proved apparatus are illustrated by way of example in the accompanying drawings in which:—

Fig. 1 is a diagrammatic view showing a deformation curve illustrative of the opera- 90 tion of the apparatus.

Complementary Figs. 2, 2^a are a longitudinal section partly in side elevation of a first constructional form of the invention.

Fig. 3 is a side elevation partly in sec- 95 tion, drawn to a larger scale, of the details of the mechanism for automatically regulating the load on the valve.

Fig. 4 is a corresponding end elevation, partly in section on the line IV—IV of 100 Fig. 3.

Fig. 5 is part horizontal section on the line V—V of Fig. 3.

Complementary Figs. 6, 6^a and 7, 7^a are similar longitudinal sections partly in side 105 elevation, of respectively a second and third constructional form of the invention.

In these figures, A is the tube to be "self-

hooped" resting upon suitable brackets B. A mandrel C is inserted at the beginning of the operation in the tube and so as to extend throughout the entire length of the tube. Liquid under pressure is confined in the annular space F comprised between the internal wall of the tube A and the external wall of the mandrel B; this space being limited by a fixed closure or joint D at the inner 10 end and a head or joint E movable with the mandrel at its outer end.

The mandrel C projects outwardly at the rear. An axial passage c formed in the mandrel C and the rearward extension C¹ of the latter, establishes communication between the annular space F and a discharge passage c¹ formed in the extension C¹. The passage c¹ is normally closed by a loaded valve.

In the examples shown, the valve consists of a ball G pressed upon its seat by a finger H carried by a lever I that is fulcrumed on a bracket J fixed on the extension C¹ of the mandrel. A heavy disk K is slidably mounted on the lever I. It is clear that the load on the valve G will vary with the position of the weight K on the lever I. It is also clear that the valve G subjected on one face to the action of the weighted lever I-K, and on its other face to the pressure prevailing in the annular space F, will remain pressed upon its seat so long as this latter pressure is less than or is equal to the load, and that the valve will rise so soon as the said pressure will become greater than the load.

The mechanism for insuring that the variations of the load on the valve shall follow a given law determined by the movements of the mandrel, is constructed as follows in the illustrated examples.

A cord L attached at one end to the weight K, passes over guide pulleys m m¹ carried by a bracket M fixed to the free end of the extension C¹ of the "self-hooping" mandrel, and is attached at its other end to a slider N. The latter is held and guided at one point in notches in the extension C¹ of the mandrel, and at another point it engages in a guide slot O by means of an anti-friction roller n which it carries at the said other point. This slot is formed in a fixed plate P, and preferably in a part p fixed to this plate.

It is clear that any outward movement of the mandrel C-C¹ will produce a corresponding displacement of the slider N, and the latter which is compelled to follow the guide O, will act upon the cord L, and thus pull the weight K along whereby the load on the valve G will be increased.

The three constructional examples illustrated in the drawings differ from one another merely by the mechanism for displacing the mandrel C-C¹.

In the example shown in Figs. 2, 2^a, the extension C¹ of the mandrel C carries at an intermediate point of its length, a piston C²

working in a cylinder Q into the forward chamber q of which the mandrel C extends through a stuffing box. This forward chamber q receives liquid under pressure delivered by a pump R through a pipe S fitted with a cock s. A discharge pipe T fitted with a cock t, allows of exhausting the liquid from the chamber q into the tank U of the pump.

The liquid under pressure can be admitted to the annular space F through a passage c² that is formed in the mandrel C and opens into a union C³ fitted with a non-return valve or a suitable closing device C⁴.

The annular space F having been filled, the union C³ is closed, and the liquid is delivered by the pump R through the pipe S into the chamber q of the cylinder Q. The pressure of the liquid upon the forward face of the piston C² tends to move the latter in the rearward direction. This displacement however can take place only at the instant when the pressure in the annular space F and in the passage c communicating therewith exceeds the load on the valve, which load is controlled by the position of the weight K. This pressure can be ascertained by means of a pressure gage V and may be read off a scale marked on the plate p.

By suitable operation of the pump the desired pressure produced in the annular space F may be maintained, and thus the entire length of the internal wall of the tube may be subjected to this pressure for any desired length of time.

Further by suitably operating the pump the pressure in the space F may be raised so as to cause the loaded valve to lift, and consequently exhaust liquid through the passage c¹ (Fig. 3), which will allow the piston C² to be displaced in the rearward direction. The amount of this displacement may be regulated very exactly in such a manner that it will produce by the action of the slider N on the cord L, a determined displacement of the weight K which will increase the load on the valve by the desired amount. In this way the tube A will be subjected for a small fraction of the displacement of the piston, to a higher pressure corresponding to that of the new load on the valve. A suitable operation of the pump or of the isolating cock will enable this new pressure to be maintained for a desired length of time, and so on.

It will be perceived that the displacements that are imparted successively to the piston C² can also be reduced to any desired extent.

In practice, the interior of the tube can be subjected over zones of continuously diminished lengths, to pressures increasing according to a given law, by suitably determining the shape of the guide O.

When the operation is finished, the ad-

mission of liquid to the chamber *q* is shut off by operating the cock *s*. This chamber is emptied by opening the cock *t*, and thus the mandrel *C* can be returned into its initial position by forcing liquid into the space *F* through the union *C³* the closing device *C⁴* of which has previously been opened.

W is a discharge passage opening into the passage *T*, which can be placed into and out of communication with this passage by the operation of a cock *w*.

In the example illustrated in Figs. 6, 6^a, the annular space *F* is filled through a union fitted with a closing device provided at the end of the outer extension *C¹* of the mandrel *C* and into which the passage *c* opens. On the forward end of the tube to be shaped there is screwed a cylinder *Q* which is connected to the pump *R* (not shown) through the passage *S*. The displacements of the mandrel are produced by the thrust of the liquid upon the forward end of the mandrel *C*.

In the modification illustrated in Figs. 7, 7^a, the invention is shown applied in combination with the apparatus forming the subject matter of an application for patent filed March 31, 1919, Serial No. 286,501, for "apparatus for the manufacture of metal tubes of great strength by means of internal hydraulic pressure."

The tube *A* is held between two crossheads *X*, *X¹* connected together by tie-rods *Y*. The rear crosshead *X¹* serves as an abutment for the rear joint *D* limiting the annular space *F*.

In the front crosshead *X* which comprises a differential piston *Z* similar to the one described in an application for patent dated March 31, 1919, Serial No. 286,494, and serves as a union for the admission of the liquid under pressure, the liquid is admitted into a chamber *q*, and passes through the axial passage *z* in the piston *Z*, on its way to act against the front end of the mandrel *C*.

The filling of the space *F* is done as in the preceding example, through a union fitted with a closing device provided at the end of the projecting part *C¹* of the mandrel *C*.

In all the hereinbefore described constructional examples, the "self-hooping" operation is effected in a continuous clearly determined and perfectly adjustable manner; it does not require any stoppage for passing from the treatment of one zone of the tube to the treatment of the next following zone.

What I claim is:—

1. An apparatus for effecting the "self-hooping" of metal tubes by consecutive zones by means of a liquid under pressure forced into the annular space between the internal wall of the tube and a mandrel, characterized by a mechanism that allows of producing by gradual displacement of the

said mandrel, a gradual increase of the pressure in the said annular space; the said displacement being automatically limited by a discharge of liquid from said space through an axial passage of the mandrel 70 opening into a discharge passage formed in an outer extension of the said mandrel and normally closed by a loaded valve whose load is regulated automatically according to a determined law of variation (corresponding to the variations of the strains to which the various sections of the tube are subjected) by a mechanism controlled by the displacements of the mandrel and also simultaneously by a guiding cam. 80

2. An apparatus as claimed in claim 1, wherein the loaded valve that limits the rise of pressure in the annular space between the "self-hooping" mandrel and the tube, is of the steelyard type, the loading weight being 85 slidable along a lever fulcrumed on the outer extension of the mandrel and being connected by a cord to a slider which is guided on the said mandrel extension and also in a cam slot formed in a fixed part. 90

3. An apparatus as claimed in claim 1, wherein the displacement of the mandrel is produced by the action of the pressure liquid upon a piston provided on the outer extension of the mandrel, and working in a 95 cylinder in which the said mandrel is guided.

4. An apparatus for effecting the "self-hooping" of metal tubes comprising a mandrel longitudinally movable in the bore of the tube being treated and carrying a head in one end of the tube with the mandrel in its initial position, a stationary closure for the other end of the tube, said mandrel forming with the wall of the tube an 100 annular chamber to receive the fluid-pressure to be compressed therein between the stationary closure and the head moved inwardly by the mandrel, said mandrel having a duct leading from the annular chamber to a discharge outlet to permit the escape of the fluid-pressure to vary the pressure within said chamber, a valve controlling the discharge outlet, and mechanism actuating the valve to regulate the escape of the fluid-pressure to control the pressure in the annular chamber during the compressing movement of the mandrel. 110

5. An apparatus for effecting the "self-hooping" of metal tubes comprising a mandrel longitudinally movable in the bore of the tube being treated and carrying a head in one end of the tube with the mandrel in its initial position, a stationary closure for the other end of the tube, said mandrel 120 forming with the wall of the tube an annular chamber to receive the fluid-pressure to be compressed therein between the stationary closure and the head moved inwardly by the mandrel, said mandrel having a duct 125

125

130

leading from the annular chamber to a discharge outlet to permit the escape of the fluid-pressure to vary the pressure within said chamber, a valve controlling the discharge outlet, mechanism actuating the valve to regulate the escape of the fluid-pressure to control the pressure in the annular chamber during the compressing movement of the mandrel, and a guide calibrated to the varying stresses to be applied to the wall of the tube controlling the operation of the valve-actuating mechanism to vary the opening and closing of the valve to regulate the fluid-pressure in the annular chamber to apply the required stresses.

6. An apparatus for effecting the "self-hooping" of metal tubes comprising a mandrel longitudinally movable in the bore of the tube being treated and carrying a head in one end of the tube with the mandrel in its initial position, a stationary closure for the other end of the tube through which projects the mandrel, said mandrel forming with the wall of the tube an annular chamber to receive the fluid-pressure to be compressed therein between the stationary closure and the head moved inwardly by the mandrel, said mandrel having a duct leading from the annular chamber to a discharge outlet in the outer end of the mandrel to permit the escape of the fluid-pressure to vary the pressure within said chamber, a valve controlling the discharge outlet, mechanism carried by the mandrel to actuate the valve, and a guide calibrated to the varying stresses to be applied to the wall of the tube engaging the valve-actuating mechanism during the movement of the mandrel to operate said mechanism to actuate the valve to regulate the escape of the fluid-pressure from the annular chamber to vary the application of pressure therein according to the required stresses.

7. An apparatus for effecting the "self-hooping" of metal tubes comprising a mandrel longitudinally movable in the bore of the tube being treated and carrying a head in one end of the tube with the mandrel in its initial position, a stationary closure for the other end of the tube through which projects the mandrel, said mandrel forming with the wall of the tube an annular chamber to receive the fluid-pressure to be compressed therein between the stationary closure and the head moved inwardly by the

mandrel, a cylinder and coacting piston attached to the mandrel, means for supplying fluid-pressure to the cylinder to move the piston and attached mandrel, said mandrel and piston having a duct leading from the annular chamber to a discharge outlet in the outer end of the piston-rod to permit the escape of the fluid-pressure from the annular chamber to vary the pressure in said chamber, a valve controlling the discharge outlet, mechanism carried by the piston-rod to actuate the valve, and a guide calibrated to the varying stresses to be applied to the wall of the tube engaging the valve-actuating mechanism during the movement of the mandrel to operate said mechanism to actuate the valve to regulate the escape of the fluid-pressure from the annular chamber to vary the application of pressure therein according to the required stresses.

8. An apparatus for effecting the "self-hooping" of metal tubes having an external longitudinal profile tapering relatively to the axis of the tube, from one end thereof to the other, either continuously or in consecutive steps, comprising a mandrel longitudinally movable in the bore of the tube being treated and carrying a head in one end of the tube with the mandrel in its initial position, a stationary closure for the other end of the tube through which projects the mandrel, said mandrel forming with the wall of the tube an annular chamber to receive the fluid-pressure to be compressed therein between the stationary closure and the head moved inwardly by the mandrel, said mandrel having a duct leading from the annular chamber to a discharge outlet in the outer end of the mandrel to permit the escape of the fluid-pressure to vary the pressure in said chamber, a valve controlling the discharge outlet, mechanism responsive to the action of a cam carried by the mandrel to actuate the valve, and a guide having a camming surface profiled to correspond to the external longitudinal profile of the tube to engage the cam-responsive mechanism to operate the valve to regulate the escape of the fluid-pressure from the annular chamber during the compressing movement of the mandrel.

In testimony whereof I have signed this specification.

EUGÈNE SCHNEIDER.
